FIG. 5.

UNITED STATES PATENT OFFICE.

EDWARD J. McGOWAN, OF NEW YORK, N. Y.

BALLOT-BOX.

1,275,579.

Specification of Letters Patent. Patented Aug. 13, 1918.

Application filed March 8, 1918. Serial No. 221,132.

To all whom it may concern:

Be it known that I, EDWARD J. McGOWAN, a citizen of the United States, residing in the borough of Manhattan, city, county, and 5 State of New York, have invented certain new and useful Improvements in Ballot-Boxes, of which the following is a specification.

My invention relates to improvements in 10 ballot boxes and particularly to the type of box having a cover with a slot therein adapted to permit the deposit of ballots therethrough.

My invention has for its object the provision 15 of means within the box itself whereby the slotted aperture may be closed, after the ballots have been cast, by a metallic plate, and such plate may then be locked in its closed position by the same locking 20 means by which the closed cover is locked to the box.

It has for its further object the provision 25 of means, within the box, for locking the slot-closing plate in its open position while the box is in use for receiving the deposit of ballots and exterior locking means independent of the interior means for locking the cover in its closed position.

Further objects of my invention are to 30 afford simple and convenient means for securing and protecting the contents of the box after the polls are closed, the ballots counted and the tally sheets certified and deposited in the box with the redeposited 35 ballots by the tally clerk or other official of the board of election inspectors, or such officials as have charge of the count in the first instance at the polling place, whose duty it is to seal the box and deliver it to its 40 custodian pending a recount, if any; also the provision of a box having no exterior parts which would interfere with its being stacked and preferably of rectangular shape, the cover or lid being flat to admit of stacking.

In the preferred form of my invention, 45 further objects are to provide such a self-contained structure and in which the slot must be closed in order to lock the cover and wherein the slot can not be opened 50 until the cover is opened, and wherein, further, closing the cover automatically locks both the slot and the cover.

Heretofore it has been customary to seal 55 the slot by means external to the box, and to lock the box by an exterior lock, customarily a padlock. It has been found that

devices used for these purposes are readily tampered with, and by reason of their exposed character, such devices invite examination by the curious, and the boxes so 60 protected are frequently damaged as to their seals, not only maliciously but also unintentionally, so that their condition is rendered such as to afford no guaranty as to the inviolability of their contents. 65

By my improvements these difficulties are overcome and the greatest security for the ballots as returned is obtained, my ballot box being both fool- and knave-proof to such a degree that any tampering therewith 70 is a matter at once capable of detection, since the security of the box when sealed and locked can only be violated by use of means adapted to break it open. 75

The above recited objects and advantages, 80 with others hereinafter set forth, are attained by my invention, whose preferred structural embodiment is illustrated in the accompanying drawings forming a part of this specification.

In these drawings, Figure 1 illustrates a perspective view of a standard form of ballot box, such as is used in the State of New York, having a ballot-receiving slot and exterior fastening means comprising 85 a hasp and staple adapted to receive a padlock; Fig. 2 shows the sealing and locking mechanism on the interior of the raised lid, the box body being broken away; Fig. 3 is a view corresponding to Fig. 2, the said 90 mechanism being in its alternative position; Fig. 4 is a sectional view on line IV—IV of Fig. 2; Fig. 5 is a sectional view on line V—V of Fig. 3. 95

Throughout the several figures like numerals indicate like parts.

1 is the ballot box, having the hinged lid 2 with the slotted aperture 3 therein, and the hinged hasp 4 for engagement with the staple 5 on the box front 6, and adapted 100 to receive a padlock 7. Within the box front 6 and rigidly affixed and permanently secured thereto is the spring lock 8 having the detents 9. Upon the inside of the cover 2 are guides 10, 10 within which is a slide- 105 able plate 11 having a flange 12 adapted to engage with a leaf spring catch 13. The plate has a rectangular opening 14 against whose opposite walls the stop 15 fixed on the lid is adapted alternately to bear to 110 limit motion of the plate in either direction. The upper edge of the plate is bent upward

to form an upstanding flange 16 and is then bent inward to form an inturned member 17 having a slot 18 adapted to receive the detents 9 of the spring lock 8 mounted on 5 the front wall of the box and provided with the key-hole 19 therethrough for unlocking it. The cover is suitably hinged at 20, 20 to the box body.

The method of use of this improved ballot box is as follows: The cover being open, the slideable plate 11 is moved into the position shown in Figs. 1, 2 and 4, so as to present an unobstructed slot for the deposit of 10 ballots, being held in retracted position by engagement of its flange 12 with the spring clip 13. The cover is then closed and the hinged hasp 4 is engaged with the staple 5 and padlocked thereto. After the polls are closed and the canvassing board open the box to 15 count the ballots, the plate 11 is released from the spring clip and advanced so as to close the slot, the wall of the opening 14 abutting against the stop 15, as shown in Figs. 3 and 5. The counted ballots and the return 20 thereof by the enumerators is then placed within the box and the lid closed. By moving the slideable plate against the stop 15, the inturned flange member 17 is brought in position so that upon closing the cover the slot 25 18 in the member 17 registers with the detents 9 of the spring lock 8 and the cover is held thereby in closed position, the plate being locked in closed position as well, whereby the slot 3 in the cover is sealed. The sealing 30 and locking plate is of metal, thus the locked box constitutes a self-contained structure of such strength that it can not be opened readily save by unlocking, and its contents can not be injured, abstracted nor altered 35 through the sealed slot. The self-contained feature of this structure is a further advantage in that by the avoidance of external projections or fastening means above the cover, the boxes, when placed in a safe de- 40 posit vault or other storage warehouse, may be stored with economy of space, since they may be readily piled or stacked. The hasp-lock may be also employed as an added security if desired, but this is not essential 45 when the spring lock engages the cover.

Having thus described the preferred embodiment of my invention, whose structural details are susceptible of modification without departing from the spirit of my disclosure, and without desiring to be understood as limiting my invention to the particular form thereof shown and described, I claim:

1. A ballot box having a lid with a ballot-receiving aperture therein, means carried by 55 said lid adapted to close said aperture, and means adapted to lock both said closing

means and said lid in closed positions, said closing means and said locking means being located wholly within the box, said locking means becoming automatically operative 60 upon the closing of the lid.

2. A ballot box having a lid hinged thereto with a ballot-receiving-slot therein, closing means located wholly within the box adapted to be moved to close said slot, and 70 when so moved to be locked in closed position, and locking means located wholly within the box adapted to be operated by shutting the lid and to coöperate with said closing means to lock simultaneously both said 75 closing means and said lid in closed positions.

3. A ballot box having a lid hinged at one side thereof, and a ballot-receiving-slot therein, closure means within said lid 80 adapted to be moved to close said slot, and locking means fixed to the opposite inner side of said box adapted to engage said closure means when in closed position, said locking means being operable both to lock 85 said lid and to lock said closure means, and being automatically operated by the closing of the lid.

4. A ballot box having a lid with a ballot-receiving-aperture therein, a plate adapted 90 to slide in guides on the inner side of said lid, said plate having an aperture therein adapted to register with said ballot-receiving aperture when moved in one direction, and to close the same when moved in 95 the opposite direction, a stop limiting the movement of said plate in either direction, means adapted to lock said plate in its slot-exposing position, and means adapted to lock said plate in its slot-closing position. 100

5. A ballot box having a cover with a slot therein, a spring lock upon the interior of a wall of said box, means within said cover adapted to engage said spring lock, said means comprising a slotted plate adapted to 105 be moved upon said cover alternately to expose said slot and to close same, said plate having an extension adapted to engage said lock when the plate is in slot-closing position, whereby closing the cover simultaneously locks both said box cover and said slot-closing plate.

6. A self-contained ballot box adapted to be stacked and having a flat lid, said lid having a ballot-receiving slot therein, means 115 within said lid adapted to close said slot, and means within said box adapted to maintain said slot closed while the lid is closed, said means being adapted to operate automatically upon and by the closing of the lid. 120

EDWARD J. McGOWAN.
